United States Patent Office

Des. 177,529
Patented Apr. 24, 1956

177,529

FOOT ROLLER

William H. McDermott, Sr., Toledo, Ohio

Application May 28, 1953, Serial No. 25,226

Term of patent 14 years

(Cl. D83—1)

In the drawings,

Fig. 1 is a side view of a foot roller, showing my new design, and

Fig. 2 is an end view thereof.

I claim:

The ornamental design for a foot roller, substantially as shown.
